UNITED STATES PATENT OFFICE.

WILLIAM H. ROSE, OF JERSEY CITY, NEW JERSEY.

AIR DEFLECTOR.

Application filed March 30, 1927. Serial No. 179,557.

My invention relates to air deflectors, and refers particularly to devices of this character suitable for use with open windows.

One object of my device is an air deflector 5 simple in construction and of low cost of production.

Another object of my device is an air deflector which can be packed and shipped in flat form, thus saving space and cost of 10 package and overcoming the danger of breakage incident to devices of fixed angular formation.

Another object of my device is an air deflector having a wire netting of transparent, air impervious material, the free, sharp 15 ends of the wire being protected to prevent damage, or injury, to a person handling the device and which will at the same time present an attractive and pleasing appearance.

20 A consideration of my specification and its accompanying drawings will show that my device possesses all of the above mentioned and other desirable attributes.

I have found that paper fiber board is a 25 strong, durable and inexpensive material for devices of the character described and I take advantage of these properties of this material as well as the possibility of bending under certain conditions without breakage.

30 I have further found that wire netting covered with a transparent air-impervious material is a most efficient material from which to form the transparent portions of my device, because of its cheapness, freedom 35 from breakage and durability.

As the free, cut edges of wire netting present a serious objection to its use, because of its liability to scratch, or injure, the hands of the user, I have found a means 40 whereby this danger may be avoided, while at the same time the appearance of the device is greatly enhanced over one having exposed wire ends.

In order to accomplish this last mentioned 45 desirable quality, I compress, or impress, the edges of the paper fiber board around the opening to be covered by the netting, and then insert the netting within the recess thus formed, the cut edges of the netting 50 being below the surface of the device, and thus protecting the user from danger incident to the sharp ends of the netting wires. This form of construction also enhances the 55 appearance of the device and makes it more attractive.

The device of my invention, therefore, is

a cheap, effective, showy, and attractive air-deflector.

In the accompanying drawings illustrating modified forms of the device of my invention, similar parts are designated by 60 similar numerals.

Figure 1 is a perspective view of one form of my device mounted within a window frame.

Figure 2 is a front view of the blank of 65 my device.

Figure 3 is an enlarged cross-section through the line 3—3 of Figure 2.

Figure 4 is an enlarged cross-section through the line 4—4 of Figure 3. 70

Figure 5 is a cross-section similar to Figure 4 showing a modified form of netting attachment.

The particular form of the device of my invention shown in the accompanying drawings comprises a blank, or sheet, of paper fiber board 10, having the two score-lines 11, 11 and 11, 11; allowing the two triangular shaped end pieces 12, 12 to be bent at right angles to the base 13 without tearing 80 the blank. 75

Within the base 13 are two recessed openings as 14, formed by impressing, or forcing outwardly, the edge 15 of the base surrounding the opening, thus forming a recess 16. 85

Reposing within this recess is a sheet of wire netting 17 covered with a transparent flexible material which allows the passage 90 of light but prevents the passage of air or water.

The netting 17 is maintained in place by a plurality of wire staples 18, 18 passing through the netting 17 and the recessed portion 15 and the base 13. 95

In the modification shown in Figure 5, the netting is maintained in position by wire-stitching 19.

The operation of the device is as follows:

The blank is folded, or bent, along the 100 score-lines 11, 11 until the triangular end pieces 12, 12 are at right angles to the base 18. The end pieces 12, 12 are then inserted between the opposite sides 20, 20 of a window-frame 21 and attached thereto by means 105 of nuts, screws, or other suitable fastening means 22, 22.

The device, therefore, presents a cheap and effective air deflector, comprising a blank of paper fiber board capable of being shipped, 110 or stored, in compact, flat form, and which

may be readily bent into the desired shape and easily attached to a window frame. The construction of the device being such that the raw edges of the wire netting are within 5 a base recess, thus presenting an attractive appearance and preventing the damages incident to an exposed edge of sharp wire ends.

I do not limit myself to the particular size, shape, number, arrangement or material of 10 parts as shown and described as these are given simply as a means for clearly describing the device of my invention.

What I claim is:—

1. In an air-deflector, in combination, a 15 paper fiber board parallelogram blank having an opening therein and having extended triangular extensions at each end thereof, score lines between the parallelogram portion and the triangular portions, a depressed 20 recess in the parallelogram portion around the opening, a wire netting set within the recessed opening, a transparent air-nonpermeable substance carried by the netting and means for attaching the netting within the 25 recess.

2. In an air deflector, in combination, a paper fiber board parallelogram blank hav-

ing an opening therein and having extended triangular extensions at each end thereof, 30 score lines between the parallelogram portion and the triangular portions, a depressed recess in the parallelogram portion around the opening, a wired transparent, air-nonpermeable material set within the recess and wire means attaching the wired material within the recess.

3. In an air deflector, in combination, a paper fiber board parallelogram blank having an opening therein and having extended triangular extensions at each end thereof, 40 score lines between the parallelogram portion and the triangular portions, allowing the triangular portions to be bent at right angles to the parallelogram portion, a depressed recess in the parallelogram portion 45 around the opening, a wired transparent, air-nonpermeable material set within the recess and wire means attaching the wired material within the recess.

Signed at New York city, in the county of 50 New York and State of New York, this 29th day of March, 1927.

WILLIAM H. ROSE.
